(57) **CLAIM**

The ornamental design for a multi-chamber pouch, as shown and described.

DESCRIPTION

FIG. 1 is a front perspective view of a first multi-chamber pouch embodying the new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof; and,

FIG. 7 is a bottom plan view thereof;

FIG. 8 is a front perspective view of a second multi-chamber pouch embodying our new design;

FIG. 9 is a front side elevation view of the second multi-chamber pouch;

FIG. 10 is a rear side elevation view of the second multi-chamber pouch;

FIG. 11 is a right side elevation view of the second multi-chamber pouch;

FIG. 12 is a left side elevation view of the second multi-chamber pouch;

FIG. 13 is a top plan view of the second multi-chamber pouch; and,

FIG. 14 is a bottom plan view of the second multi-chamber pouch.

The broken lines are included for the purpose of illustrating the portions of the multi-chamber pouch that form no part of the claimed design.
